INSTRUCTIONAL VOTING MACHINE

Carl R. Finegan, Elyria, Ohio

Application September 4, 1951, Serial No. 244,920

1 Claim. (Cl. 35—8)

1

My invention relates in general to a device for instructing voters in the use of a voting machine.

In the past few years many political subdivisions of the country have been installing voting machines in place of the old paper ballots. Since these voting machines are expensive and will register the vote of many voters there are relatively few of the machines as compared to the number of voters using them. Thus, the individual voter does not have an opportunity to spend much time learning to operate the machine. Generally the voter tries to learn how to operate the machine on the day of the election instead of making a special trip to the voting place before the election day. I have discovered that it is a great advantage to the public to have some means whereby the public may easily learn how to operate the voting machine before going to the poll or voting place. It is generally understood that to teach the public how to use the machine, the machine must be taken to the public since the voters will not go to the voting place to learn to operate the machine before election day.

Therefore, one of the objects of my invention is to provide an inexpensive instructional device which may be easily constructed in large quantities and distributed to the public.

Another object of my invention is to provide a voting machine instructional device comprising a keyboard representing a voting machine and having indicators operable the same as those on the regular voting machine.

Still another object of my invention is to provide a means for instructing a high percentage of the voters in the use of the voting machine without causing the voters to go to the place of voting.

Other objects and a fuller understanding of my invention may be had by referring to the following description and claim, taken in conjunction with the accompanying drawings, in which:

Figure 1 is a front elevational view of my instruction device as representing a voting machine;

Figure 2 is a sectional view along the line 2—2 of Figure 1;

Figure 3 is a sectional view along the line 3—3 of Figure 1;

Figure 4 is a back elevational view, the back cover having been removed, of a modification of my instruction device;

Figure 5 is a sectional view along the line 5—5 of Figure 4; and

Figure 6 is a sectional view along the line 6—6 of Figure 4.

2

My voting machine instruction device comprises generally a keyboard 10 having a back side 11 and a face side 12. The keyboard 10 is supported by a housing 19 having a back cover 31, which has been removed in Figure 4. The face side 12 is a representation of a voting machine used by the voter and thus includes party or office rows 13 and 14 respectively, of candidates' names. The party row 13 is illustrated as having candidates' names 15 and 16, while the party row 14 is illustrated as having candidates' names 17 and 18. It is understood that any number of candidates' names may be placed on my keyboard 10, and that I have placed three names for each party by way of example only. The keyboard 10 has arcuate slots 20 next adjacent each of the candidates' names 15, 16, 17, 18 and 19. I have provided voting indicators 21, 22, 23, and 24 for each of the candidates' names 15 to 18, respectively. These voting indicators 21 through 24 are pivotally mounted on the face side 12 of the keyboard 10 with each voting indicator next adjacent its respective candidate name. The voting indicators are pivotally mounted in rows substantially parallel to the party rows. In my drawings I have illustrated the voting indicators as being riveted to the keyboard 10 such as indicated by number 29 in Figure 3, the voting indicators for the offices being secured in the same manner as those for the questions.

Extending from the back side of each of the voting indicators 21, 22, 23 and 24 are stop portions 25, 26, 27, and 28 respectively. Each stop portion extends through its respective arcuate slot and also outwardly from the other side of the voting indicator to serve as a handle. The voting indicators and their respective handles or stop portions are thus annularly movable toward the respective candidate name to a voted position and away from the respective candidate name to a non-voting position with the stop portions 25, 26, 27 and 28 reciprocally moving in the respective slots 20. I have further provided my keyboard 10 with a curtain handle 32 and a control lever 33 fastened thereto for angular movement therewith. The curtain handle 32 is pivotally mounted on the face side 12 while the control lever 33 is mounted on the back side 11. A rivet 34 extending through the curtain handle 32, the keyboard 10 and the control lever 33, pivotally mounts the handle 32 and the control lever 33 on the keyboard 10. An arcuate slot 35 is also provided next adjacent the curtain handle 32. A member 36 extending through the arcuate slot 35 connects the curtain handle 32 and the control lever 33 for angular movement of the con-

trol lever 33 with movement of the curtain handle 32.

In the drawings the curtain handle is in the curtain open position. When the curtain handle is moved to the curtain closed position the voter can move the desired voting indicators to voted position. Movement of the curtain handle from curtain closed position to curtain open position, will cause all of the voting indicators to be moved and returned to their original position prior to voting. This control of the voting indicators by the curtain handle is accomplished through a single panel member 37 of sheet-like material having a plurality of arcuate slots 38 each of which is generally aligned with its respective of the arcuate slots 20 in the keyboard 10. As best illustrated in Figure 3, each stop portion of the voting indicators extends through its respective slot in the keyboard 10 and in the panel member 37.

The panel member 37 is supported for reciprocal movement on the back side 11 of the keyboard 10 by L-shaped supports 39 which also serve as guides. In this particular instance the control lever 33 moves the panel member 37 in one direction and gravity moves it in the opposite direction to put it in position for voting. The arcuate slots 38 are of correct length so that the ends 40 will push the stop portions of the voting indicators to the original or non-voted position. Movement of the curtain handle to the position illustrated in Figure 1 causes control lever 33 to move the panel member 37 and return all of the voting indicators to non-voted position by means of slot ends 40 and stop portions including stop portions 25 to 28. Movement of curtain handle 32 to curtain closed position allows panel member 37 to fall downwardly in Figure 1 and align slots 38 with slots 20 so that the desired voting indicators may be moved to voted positions.

An instructor uses the device to instruct voters in much the same manner as taught by my co-pending application for Instructional Voting Machine, Ser. No. 42,858, filed August 6, 1948.

In Figure 4 I have illustrated a modification consisting of the preferred structure illustrated in Figures 1 to 3 and the addition of party levers 44 and 45 for the respective party or office rows 13 and 14. The party rows 13 and 14 are provided with reciprocally movable members 46 and 47 respectively. These members 46 and 47 have arcuate slots aligned with the arcuate slots in the keyboard 10. Movement of lever 44 causes downward movement of member 46 in Figure 4 by means of flexible cord 49 while the curtain handle is in curtain closed position. The ends 50 of the slots 51 in the member 46 abut stop portions 25 and 26 to move the voting indicators 21 and 22 along with all the other voting indicators in that row to the voted position. Guides 52 mounted on back side 11 cooperate with guide slots 53 in the members 46 and 47 to keep their movement parallel to the movement of panel member 37.

The operation of the modified design illustrated in Figures 4, 5, and 6 is substantially the

same as that of my herein referred to prior application in so far as the voter is concerned.

Although the invention has been described with a certain degree of particularity in its preferred form, it is understood that the present disclosure of the preferred form has been made only by way of example and that numerous changes in the details of construction and the combination and arrangement of parts may be 10 restored to without departing from the spirit and the scope of the invention as hereinafter claimed.

I claim:

An instruction device for instructing a voter in the correct manipulation of a voting machine 15 comprising, a keyboard having a back side and a face side with a representation of a voting machine used by the voters and including office rows of candidate names for offices, voting indicators, one for each name, pivotally mounted in rows on 20 the face side of said keyboard with each indicator movable in a first direction angularly towards its respective name to a voted position and movable in a second direction angularly away from its respective name to a non-voted position, 25 a single panel board reciprocally movable on the back side of said keyboard and in a line of movement other than parallel to said rows of voting indicators to a closed curtain position and to an open curtain position, said keyboard and said 30 panel board having rows of somewhat arc shaped slots, one in each board for each indicator, and co-aligned when said panel board is in said closed curtain position, each voting indicator having a stop portion extending through the respective 35 slot in the keyboard and into the respective slot in the panel board, and a curtain handle pivotally mounted on the face side of said keyboard for movement angularly in one direction to an open curtain position and for movement angularly in 40 the opposite direction to a closed curtain position, a control lever on the back side of said keyboard and secured to said curtain handle for angular movement therewith and abuttable against said panel board to effect movement of the panel 45 board to its open curtain position upon movement of the control lever to its open curtain position and to effect movement of the panel board to its closed curtain position upon movement of the control lever to its closed curtain position, said 50 panel board having portions defining ends of the respective slots and abuttable against said stop portions to move the voting indicators to their non-voted position upon movement of the curtain handle and the panel board to the open curtain position.
